UNITED STATES PATENT OFFICE.

ARTHUR D. COULTER, OF SEATTLE, WASHINGTON.

FIREPROOF SAFE.

1,304,855.

Specification of Letters Patent. Patented May 27, 1919.

Application filed July 15, 1918. Serial No. 244,998.

To all whom it may concern:

Be it known that I, ARTHUR D. COULTER, a citizen of the United States, and resident of the city of Seattle, county of King, and 5 State of Washington, have invented certain new and useful Improvements in Fireproof Safes, of which the following is a specification.

My invention relates to safes and particularly to safes that are intended for protection against fire, rather than against burglars. The object of my invention is to provide a cheaply constructed safe which will have great fire resisting qualities so that it 10 may be used for a wide variety of purposes where it is desired to protect papers and other valuable property against destruction by fire.

The particular features of my invention 20 which I deem to be new and patentable will be hereinafter described and then particularly defined by the claims.

In the accompanying drawings, I have shown my invention embodied in a safe 25 which is of the construction which I now most prefer to use. I am aware, however, that many of the details of the construction of this safe, particularly in the metal binding and holding members, may be widely 30 varied, without, however, changing the essential characteristics of the invention.

Figure 1 shows in perspective a safe constructed in accordance with my invention, with portions of the walls broken away and 35 the door omitted.

Fig. 2 is a perspective showing the inside surfaces of one of the corner caps.

Fig. 3 is an edge view in elevation, of the same cap.

40 Fig. 4 is a perspective of an end of one of the angle bars used for protecting the corner edges of the safe.

Fig. 5 is a section of a corner of the safe.

In carrying out my invention, I employ 45 for the side walls of the safe, slabs of a material which is highly resistant to heat, as the chief purpose of this safe is to protect its contents against fire. For this purpose, the material which I have found most suitable, both because of its fire resisting and 50 heat insulating qualities and because of the ease and cheapness with which it may be produced, consists of an andesitic tufaceous breccia, which is found in large natural de-

55 posits and which is of such character that it

may be cheaply quarried and cut into material so as to suit my purpose.

This material, I have found to be highly 60 resistant to heat, as well as a good insulator and to have a very considerable strength and resistance to blows and breakage. It is capable of withstanding high temperatures without fracturing and is highly resistant to the transfer of heat. In other words, it is 65 a good insulator against heat.

I prepare this material by cutting it into slabs of a suitable thickness and size to each 70 form a side of the desired safe. This may be easily done as it may be cut and worked by wood working tools. Such slabs are shown as 1 in the drawings, each forming the wall of its particular side of the safe. These slabs, I bind together by metal rods 5, which are placed within the safe, the same lying 75 close alongside the inner surface of the slabs, being thereby protected against an external fire.

I employ round rods 5 and these extend 80 diagonally between opposite corners of the same side of the safe. Their location is either close against the inner wall of the slab or within a groove formed in the inner wall of the slab.

These tie rods, 5, pass diagonally through 85 the corners of the slabs 1, in which holes are bored at the proper positions to receive the rods. This may be readily done by an ordinary bit, as the material which I employ, the tufaceous breccia, may be easily bored and cut by ordinary wood cutting tools. 90 The projecting ends of the tie rods 5 are screwed or otherwise secured to caps which cover the corners of the safe. These caps may be made of cast iron and are of such size as to each form an anchor for all the 95 rods which converge to that corner. The rods and the caps, if screwed together, as I prefer to do it, would have right handed and left handed threads at opposite ends of the rods, so that the rods may be tightened 100 by turning them. In case the rods extended through the caps, their ends would be smoothed off to make a smooth surface.

In order to give a suitable depth to the engagement of the bolts with the caps, I provide the caps with internally projecting bosses 22 and recess the slabs as may be necessary to receive these.

In order to protect the corner edges of 110 the safe against breaking and chipping, I

employ protective angle bars 3, which fit over the corners and cover the joints between the edges of the slabs, which form adjacent sides of the safe. The joint shown in Fig. 5 is preferred, in which the edges of the slabs are beveled.

These binding angle bars should not be fixedly secured to the caps 2, as their expansion under the heat of a fire might displace 10 the caps and cause the bars 3 to buckle outward and thus somewhat uncover the joint between slabs.

I prefer that the angle bars merely extend under the caps and are held in place thereby. 15 I, therefore, make the caps with square sections 25 which contact directly with the slabs 1 and form recesses 23 of a size to receive the ends of the angle bars. On account of the location of the tie-rod-receiving 20 bosses 22, being located away from the extreme corner so as to be aligned with the inner surface of the slabs 1, the ends of the angle bars are provided with notches 30 to pass about the bosses 22. I also provide a 25 lug 24 which engages by its edges with the edges of the flanges of the angle bars.

By this method of construction the tie rods 5, which provide the strength to bind the parts together, are inside the safe and 30 protected from heat externally applied. They will not stretch to permit opening of cracks between the slabs, because they are not exposed to the heat of the fire.

The caps 2 to which the tie rods 5 are 35 anchored are made of cast iron which will stand a high degree of heat, and therefore are unlikely to burn away so but that they will serve as anchors for these rods.

Those of the caps which are placed at the 40 bottom of the safe may be made with lugs 21 which form supports for wheels 26.

I have not shown a door to the safe although, of course, a door would be employed. As, however, the construction and manner of 45 securing the door forms no part of my present invention, I have thought it unnecessary to illustrate the same. This door may be of any suitable construction and may be mounted and secured in any convenient and 50 suitable manner. I contemplate that the body of the door shall be of a slab of the same material as the other sides of the safe.

The tufaceous breccia, from which I make the slabs which form the walls of the safe, 55 is a material having a large number of very minute pores therein, and the material of

which the walls of the pores are formed, is highly resistant to heat. In consequence it is capable of standing a very high temperature and this for a considerable time. It 60 will not fuse at a temperature likely to occur in any ordinary fire, nor will it crack. Its heat insulating qualities are such that combustible material contained in the safe will be uninjured, even after a considerable 65 exposure of the safe to a strong fire. As the material may be very cheaply produced and the safe cheaply put together, it may be sold at a price which will permit its use in many places where the present expense of 70 an efficient fire proof cabinet would not be justified. In this safe, no reliance is made upon any metal part which is directly exposed to the temperature of the fire to maintain the integrity of the safe, with the sole 75 exception of the caps at the corners, to which the tie rods are secured. While the angle bars, 3, at the corners of the safe are exposed to the temperature of the fire, their function in holding the parts of the safe together is 80 comparatively slight. They do form a desirable finish for the safe and protect the corners against injury by chance blows. At the same time, for holding the safe together under the action of the high temperature of 85 a fire, they might be discarded. I do, however, consider them desirable for other purposes.

What I claim as my invention is:

1. A safe having its sides composed of 90 slabs of a heat resistant and insulating stone, angle bars exteriorly engaging the corner edges of the safe, tie rods lying along the inner surfaces of said slabs and extending diagonally of the safe and with their ends 95 projecting through said slabs, and caps for said rods engaging the outer corners of said slabs and overlapping the ends of the angle bars.

2. A safe having its side walls composed 100 of slabs of a heat-resistant and insulating stone, tie rods extending diagonally of and against the inner surface of said side walls, metal caps exteriorly covering the corners of the safe to which said tie rods are anchored, angle bars covering the exterior edges of the safe and having their ends extending beneath said caps.

Signed at Seattle, Washington, this 29th day of June, 1918.

ARTHUR D. COULTER.
